METHOD AND MEANS FOR TRACING DESIGNS

Application filed March 21, 1929. Serial No. 348,925.

This invention pertains to a method and means for shading designs such as pictures and the like, more particularly drawings or other designs made on paper with a pen or 5 in a similar manner.

By "designs" as used in this specification and in the accompanying claims, may be included pictures, portraits, photographic negatives, tracings and other transparencies, and 10 all similar things made by hand or otherwise which are susceptible of being shaded.

One of the objects of this invention is to provide a method by which artistic shading effects may be applied to drawings or like 15 designs in a simple and rapid manner, so as to reduce the time consumed in executing such shading.

Another object is to provide a method of applying shading to such designs, which may 20 be varied to suit the subject treated.

Another object is to provide such a method by means of which combinations of various types of shading may be applied.

Another object is to provide a method for 25 applying to a design or other sheet any special pattern or configuration in a simple and effective manner.

Further objects will appear from the following description, taken in connection with 30 the accompanying drawings, in which—

Figures 1 to 4, inclusive, illustrate successive steps in shading an illustrative drawing, in accordance with the method of this invention;

Figure 5 is a view of a sheet of shading material mounted on a backing, in accordance with this invention;

Figure 6 is a section on line 6—6 of Figure 5; and

Figure 7 is a view illustrating another application of the method of this invention.

In accordance with this invention, the drawing or design is first completed more or less in outline and the shading is then applied thereto. The shading material is prepared in the form of a very thin transparent sheet, upon which are printed or otherwise produced the cross-hatching, stipple or other type of shading or configuration to be used. 45 A material which may be used for these trans-

parent sheets is what is well known as cellophane, which may be prepared in very thin sheets which are perfectly transparent. These sheets are prepared with the various shading patterns or other configurations 55 upon them.

The design sheet or the cellophane sheet, or both, may then be coated with a suitable transparent adhesive, such as rubber frisket cement, and the shading sheet is then applied to the design by pasting the same over the area upon which the shading is to appear. The shading sheet need not originally be cut or formed to the shape of the shaded area. It is first applied to the design and then, 60 with the sheet adhering to the design, it is cut along the outline of the area to be shaded and that part covering the unshaded areas is removed, leaving the shading sheet upon the design covering the proper area. 70

In order to obtain composite shading effects, successive shading sheets may be placed upon the same area, one over the other. As the sheets are transparent, the shading of the underneath sheet will show through the covering sheet and a composite effect will be obtained. Parts of the main design may also be covered by the shading sheet and will show through those transparent sheets. 75

This process is illustrated in Figures 1 to 4, inclusive. Figure 1 represents an outline drawing, such as may be used as a fashion illustration or the like and to which suitable shading is to be applied. It may be assumed, for instance, that shading is to be applied to the clothing of the figure and also to the background along lines 1 and 2. 80

In carrying out the method, a fragment of a shading sheet 3 is suitably coated with adhesive and pasted over a portion of the design so as to cover the clothing of the figure as illustrated in Figure 2. At the same time a shading sheet 4 may be applied to the background in a similar manner, as is also illustrated in Figure 2. These sheets are then cut by a sharp instrument, such as a knife, along the outlines of the shaded area, but the sheet 3 is cut along the outlines of that part of the clothing which is to be shaded. The sheet 4 is cut along similar outlines; as, for instance, 95 100 103

the line 1. Those parts of the sheets 3 and 4 lying over areas which are not to be shaded are then removed by simply peeling the same from the design sheet. This leaves the sheets 3 and 4 in the form shown in Figure 3. It will be noted that the sheet 3 has been cut away from all unshaded areas and now covers only portions of the coat of the figure illustrated. The sheet 4 covers a patch of background of irregular outline.

The shading of the background may now be further modified by applying a second shading sheet 5 thereto. This is first applied, as described, to that general area of the design which will cover the area desired to be shaded by this second sheet. The cutting out process is then again resorted to, this time along the line 2, and the surplus of the sheet 5 is removed. This provides an area of composite shading where the sheets 4 and 5 overlap, surrounded by a margin of lighter shading where the sheet 4 alone is exposed to view. As the sheets are perfectly transparent, the shading lines of the sheet 4 are clearly seen through the sheet 5.

It will be seen that by this method shading effects of many kinds can be easily and quickly produced. A large area may be shaded by a simple method requiring no great skill and, therefore, consuming very little time. Composite shading effects may easily be obtained. As the shading sheets are printed so that the elements thereof are accurately delineated, a perfectly uniform shading is obtained over the area to which a sheet is applied. Where small unshaded areas come within a larger shaded area the shading may be obliterated with white ink or the like. In this way a great deal of time may be saved in putting in details.

This method of shading is particularly valuable in the preparation of such designs as are intended for reproduction by photographic processes. As the shading sheets are perfectly transparent, the outline drawing shows clearly through the same; and the design when completely shaded may be photographed and the complete design, including all the shading features, will be accurately reproduced on the photographs.

This method may be applied in the same manner to transparencies, such as photographic negatives, tracings and the like, intended for reproduction by printing-through processes. The shading sheet may be applied directly to the transparency and its pattern will appear on the print as a part of the complete design.

In order to provide for convenient and rapid work, the shading material may be provided in the form illustrated in Figures 5 and 6, in which the shading sheet 6 may be removably attached to a backing 7, such as the Holland sheeting used for similar purposes. The sheet is secured to the backing

by a coating 8 of adhesive, which does not harden but remains tacky. These sheets may be prepared in this manner so that while shading a drawing, the artist simply tears off fragments of the sheet 6 according to his needs. These fragments will be supplied with an adhesive coating and may be applied directly to the design. Thus, the time consumed in applying the adhesive coating is saved. The sheet 7, furthermore, provides a cover sheet which keeps the adhesive coating 8 from drying out and maintains it at all times ready for use.

The term "transparent" sheet, as used herein, is to be construed as a sheet whose transparency is such as to permit the reproduction by a photographic process of underlying designs.

This process is not limited to simple shading effects, but may be used for applying borders, special initial letters or other patterns to an underlying sheet.

As illustrated in Figure 7, borders of special design may be applied to the design sheet in accordance with this invention. The border 9 is printed on a transparent sheet 10 which is applied to the design sheet as previously described. A sheet is prepared by printing, or otherwise delineating, on the transparent sheet one or more border strips, with suitable corner devices 11, if desired. When one sheet has a number of border strips thereon, it may be perforated between strips, as indicated at 12, so as to facilitate separating the strips.

Special initial letters 13 may also be prepared on transparent sheets to be used in a similar manner. These sheets, as well as the border sheets, need not be neatly trimmed at their edges as these edges do not show on the photograph.

It will be understood, of course, that while the method has been described as a unitary method for producing a shaded design, certain features or operations thereof may be useful independently of other features or operations, and the use of such sub-combinations is contemplated by this invention and is within the scope of the appended claims. It is further obvious that various changes may be made in details of construction or operation, within the scope of the appended claims, without departing from the spirit of this invention. It is, therefore, to be understood that this invention is not limited to the specific details shown and/or described.

Having thus described the invention, what is claimed is:

1. A device for shading designs, comprising, a shaded transparent sheet coated with adhesive and having removably attached thereto by such adhesive a cover sheet.
2. A device for shading designs, comprising, a backing sheet, and a shaded trans-

parent sheet coated with adhesive and removably attached to said backing sheet.

3. A device for shading designs, comprising, a shaded transparent sheet coated with an adhesive and having means for maintaining said adhesive in tacky condition.

In testimony whereof I affix my signature this 27th day of February, 1929.

WALTER R. MANTELL.
